CLAIM

The ornamental design for an adjustable bra, as shown and described.

DESCRIPTION

FIG. 1 is a front perspective view of the adjustable bra of the present invention.

FIG. 2 is a front view of the adjustable bra.

FIG. 3 is a rear view of the adjustable bra.

FIG. 4 is a right side view of the adjustable bra; and,

FIG. 5 is a bottom view of the adjustable bra.

The broken line showing of the person is for illustrative purposes only and forms no part of the claimed design.
